UNITED STATES PATENT OFFICE.

MARGERY MAXON, OF CHICAGO, ILLINOIS, ASSIGNOR OF ONE-HALF TO LEO J. LIEBERMAN, OF CHICAGO, ILLINOIS.

HEEL PROTECTOR.

Application filed September 22, 1923. Serial No. 664,153.

To all whom it may concern:

Be it known that I, MARGERY MAXON, a citizen of the United States, and a resident of the city of Chicago, county of Cook, and 5 State of Illinois, have invented certain new and useful Improvements in Heel Protectors, of which the following is a specification.

This invention relates to novel improvements in heel protectors and has for its 10 principal object the provision of an improved construction of this character which will be highly efficient in use and economical in manufacture.

15 Among the salient objects of the invention is the provision of a device of this character constructed in such manner that the same can be mounted to embrace the heel of the shoe to protect the heel from scratches and 20 deterioration when the feet are used to manipulate the various brakes of a motor vehicle or the like. The device is not limited to any particular design of heel and from the following description it will be seen that 25 the protector can be made in various shapes in accordance with the configuration of the heel with which it is to be associated.

Other objects will appear hereinafter.

The invention consists in the combinations 30 and arrangements of parts, hereinafter described and claimed.

The invention will be best understood by reference to the accompanying drawings forming a part of this specification, and in 35 which—

Fig. 1, is a fragmentary side elevational view of a shoe showing the invention associated therewith;

Fig. 2, is a plan view of the invention; 40 Fig. 3, is a sectional view of the same taken substantially on line 3—3 of Fig. 1;

Fig. 4, is a sectional view taken substantially on line 4—4 of Fig. 1;

Fig. 5, is a fragmentary view of the heel 45 showing a slightly modified form of construction embodying the protector; and,

Fig. 6 is a sectional view of the same taken substantially on line 6—6 of Fig. 5.

Referring to the drawing showing the 50 preferred form of construction, 10 indicates a shoe having a heel 11 provided with the usual lift or tread 12. The fragmentary view of the shoe as shown in the drawing is that of a lady's shoe with a high heel construction and I have found that in

manipulating the various brakes of a vehicle that the surfaces of the heel or heels become badly scratched or otherwise damaged giving them a bad appearance and it is the object of the present invention to provide a 60 device which can be mounted to embrace the heel or heels protecting said heel or heels from damage.

The preferred form of construction as 65 illustrated in the drawing includes a body 13 preferably formed of hard rubber or other elastic and pliable material adapted to withstand hard usage and wear. The body 13 has a portion 14 covering the outer surfaces of the heel and extending to the bottom of the heel just above the lift 12 as indicated at 15. Formed as an integral part of the body is a lip 16 adapted to cover the heel covering portion of the shoe as at 17, 70 said lip being tapered downwardly toward the toe of the shoe and terminating into a ledge 18 adapted to snugly fit beneath the instep 19 as shown. The body 13 has portions 20 covering the inside surface 21 of the heel and these portions 20 are split in a 75 vertical line as at 22, the split extending across the ledge 18 as at 22'. By providing a vertical split as shown, the body can be expanded to permit mounting the protector 80 in place or to permit removal of the protector and as the material from which the body is formed is preferably of elastic material the body will have the tendency to contract 85 so as to securely hold itself in embracing position around the heel, such for example 90 as best shown in Fig. 1.

Referring to Figs. 5 and 6, showing a slightly modified form of construction. This construction includes as a part of the device a flat leaf spring 23 which is incorporated within the body as best shown in 95 Fig. 6 and the purpose of the spring is to serve as an auxiliary member to hold the body in embracing position about the heel.

While I have shown the device applied to 100 a lady's shoe it is to be understood that the device can be constructed, without departing from the spirit of the invention, to be used or associated with men's shoes.

While I have illustrated and described the 105 preferred form of construction for carrying my invention into effect, this is capable of variation and modification without departing from the spirit of the invention. I, therefore, do not wish to be limited to the 110

precise details of construction set forth, but desire to avail myself of such variations and modifications as come within the scope of the appended claims.

5 Having described my invention what I claim as new and desire to secure by Letters Patent, is:

1. Means for protecting a shoe heel from being scuffed comprising a body element of 10 relatively hard rubber adapted to engage about the heel and having integral portions adapted to engage over the breast of the heel and also having an integral lip extension adapted to protect the upper portion of the 15 heel where it rounds out from the groove adjacent the heel, said lip extension continuing forwardly and downwardly to constitute ledge portions underneath the instep and thence continuing rearward and merging into said breast portions, said ledge portions being split in substantial agreement with said breast portions, and resilient means incorporated in said body element for retaining it in embracing position about the 20 heel, substantially as described.

2. Means for protecting a shoe heel from being scuffed comprising a body element of

relatively hard rubber adapted to engage 25 about the heel leaving the heel lift exposed, said body element having integral portions adapted to engage over the breast of the heel and also having an integral lip extension 30 adapted to protect the upper region of the heel where it rounds out from the groove adjacent the heel, said lip extension continuing forwardly and downwardly to constitute ledge portions underneath the instep 35 and thence continuing rearward and merging into said breast portions, said ledge portions being split in substantial agreement with said breast portions, and resilient means incorporated in said body element for retaining it in embracing position about the 40 heel, substantially as described.

In testimony whereof I have signed my name to this specification in the presence of two subscribing witnesses.

MARGERY MAXON.
